Des. 198,642
Patented July 14, 1964

198,642

SPOON OR SIMILAR ARTICLE OF FLATWARE

James William Allen, Utica, N.Y., assignor to Utica Cutlery Company, Utica, N.Y., a corporation of New York

Filed June 14, 1963, Ser. No. 75,343

Term of patent 14 years

(Cl. D54—12)

FIG. 1

FIG. 2

FIG. 3

FIG. 4

FIG. 5

FIG. 6

FIGURE 1 is a top plan view of a spoon embodying my design;

FIGURE 2 is a side elevation of the spoon of FIGURE 1;

FIGURE 3 is a bottom view of the spoon of FIGURE 1;

FIGURE 4 is a sectional view on the line 4—4 of FIGURE 1;

FIGURE 5 is a greatly enlarged view of the central portion of FIGURE 1 showing certain details of the design; and

FIGURE 6 is a sectional view on the line 6—6 of FIGURE 5.

I claim:

The ornamental design for a spoon or similar article of flatware, as shown.
